INVALID'S TABLE

Sidney M. Bergman, Brookline, Mass.

Application November 30, 1932, Serial No. 644,974

3 Claims. (Cl. 311—40)

The present invention relates to a bed table such as may be used in hospitals for convenience in caring for patients while they are in bed.

In the present invention the table can be placed beside the patient's bed and a special top positioned above the top of the table is provided and adapted to be swung around on a vertical bearing so that the patient might have the table before him.

10 In addition to this the special top may be extended within a given limit in order to allow a proper position before the patient.

The mechanism necessary to turn the table top and position it in front of the patient is all concealed and covered and the only evidence of such operating mechanism is in the foot pedal which is positioned below the body of the cabinet of the table near the leg.

Not only does this construction offer a neat and 20 simple appearance, but there is no possibility of dust gathering in the mechanism and the table becoming dirty and unsanitary.

It may also be noted that the operation of the 25 table top in and out of the arm is so devised that no dust can settle in cracks or hollow places. The only grooves or slots, it will be noted, face downwardly.

The invention will be more fully understood 30 from the description given below in connection with the drawings showing an embodiment of the invention, in which:

Figure 1 shows a top view of the table with the top table extended.

Figure 2 shows an elevation.

35 Figure 3 shows a section on the line 3—3 of Figure 2.

Figure 4 shows a detail of the mechanism whereby the table top may be raised.

40 Figure 5 shows a bottom view of the extensible top shown in Figures 1 and 2.

Figure 6 shows a modification of the detail shown in Figure 4.

Figure 7 shows a section taken on the line 7—7 of Figure 5.

45 Figure 8 is a section taken on the line 8—8 of Figure 6, and

Figure 9 is a fragmentary side view, partly in section.

In Figure 1, the table is represented as 1. This 50 may be provided at the rear with a towel rack 2 and a handle 3. At the front of the table at the top there is a swinging tray 4, hinged by means of the hinge 5. The lower part of the table is provided with a cabinet space 6 which is closed 55 by means of the door 7 hinged by the hinges 8

at the opposite side from the position of hinging the top tray 4.

The table or cabinet is supported on legs having rubber castors 9 and at the side of the table is a lever 10 for lowering the table 11 after it has 5 been raised.

The mechanism of the operation of the table is shown more clearly in detail in Figures 3, 4, 5, 6, 7 and 8.

Supported in a side frame 12 is a plate 13 10 properly secured by bolts 14 or in any suitable manner to the side plates. The plate 13 carries a supporting bracket 15 which holds the tube 16 in which the shaft 17 extends. As indicated in Figure 8, the tube 16 may be rectangular in section and the shaft 17 similarly formed to fit inside of it.

In Figure 4, however, the shaft 17' may be round and similarly the tube 16'. A rack 18 is formed at one side of the shaft 17 as indicated 20 in Figure 6.

In Figure 4 the rack 18' is made in the form of truncated cones. A plate 19 secured to the corner post 20 of the table by means of a bolt 21 has mounted thereon a bearing 22 in which a rod 25 23 operates. The rod 23 has two pins 25 and 26. The pin 25 has in back of it a plate 27 and between this plate and the bearing 22 is a spring 24. Mounted on the plate 19 is a small pivot lever 28, one end of which engages the left hand side 30 of the pin 26, while the other end of the lever engages the pin 29 extending from a rod 30 which is supported vertically and parallel to the shaft 17.

At the end of the rod 30 is the operating foot lever 10. In the operation of the device the shaft 35 17 may be raised, the ratchet 18 being so constructed that it will pass over the rod 23. The table will not however fall down since the rod 23 is so shaped at its end as to engage the ratchet 18.

When it is desired to drop the table, the foot 40 lever is pressed, retracting the rod 23, freeing the ratchet and allowing the table to be dropped. The operation of Figure 4 is the same except that in this figure the shaft 17' may be turned around when the table top is turned to face the patient. 45

In Figure 6, however, the shaft 17 does not turn. The top 11 however turns in the bearing 31, the spring tension stud 32 engaging the cups 33 distributed about the shaft 17 so that the table top may assume any desired position.

When the top is turned towards the patient, the top may be extended as indicated more specifically in Figures 5 and 7. The shaft 17 is fixed to a center board 34 and the table top 11 may be pulled in and out with respect to the board. For accom- 55

plishing this purpose an element 35 is provided which is rectangular in shape and has flanges 36-36 which may be riveted to the inside of the table 11. A slot 37 is cut in the element 35 and a pin 38 fastened in the board 34 rides in the slot, thus limiting the motion of the table and preventing it from being taken out. A handle 39 is provided at the end of the board 34. This handle is fastened to the underside of the board 34 by a plate 40. The element 35 is cut out at the end, so as to allow room for the plate 40 and therefore allow the table to be fully closed to the edge of the handle.

The board 34 is of such a length that before 15 the pin 38 comes to the end of the slot 37, the end of the board 34 butts up against the end of the table 11.

A rubber cushion 40 is provided so that no noise will result when the top 11 is moved to its innermost position. In either modification shown in 20 Figures 4 or 6 it will be noted that the top 11 will be positioned simply upon motion of the handle 39, and that the table top may then be extended before the patient in the desired position.

25 Having now described my invention, I claim:

1. A hospital table comprising, in combination, a frame having four supporting feet, a fixed table top, a shaft, means positioning said shaft between two feet at the side of the frame, said shaft 30 being positioned upright and being free to be moved vertically and rotated, said shaft having supported at the top thereof a horizontal bracket, a handle having supporting elements fixed to said bracket on both sides where the bracket is supported by said shaft, a tray positioned on said

bracket, said tray having angles fixed thereon and positioned on both sides of the bracket and forming grooves by which said tray may be moved over said bracket whereby the tray may be extended away from the table top and rotated to the opposite side.

2. A hospital table comprising, in combination, a frame having four supporting feet, a fixed table top, a shaft, means positioning said shaft between two feet at the side of the frame, said shaft 10 being positioned upright and being free to be moved vertically and rotated, a horizontal bracket supported at the top of said shaft, a hand grip extending horizontally on one side of the bracket having ends supported on said bracket on either 15 side of the shaft, a tray extending horizontally in a direction opposite to the handle, and means mounting the tray on the supporting bracket whereby the tray may be moved over it.

3. A hospital table comprising, in combination, 20 a frame having four supporting feet, a fixed table top, a shaft, means positioning said shaft between two feet at the side of the frame, said shaft being positioned upright and free to be moved vertically and rotated, a horizontal bracket 25 supported at the top of said shaft, a hand grip having ends supported on said bracket on either side of the shaft, a tray, means forming a slot beneath said tray in which said bracket slidably fits, said means being provided with a slot directly beneath the bracket and a pin positioned in the bracket engaging the slot, whereby the movement of the tray with respect to the bracket is limited.

SIDNEY M. BERGMAN.
